SHOE MACHINE

Alfred R. Morrill, Beverly, Mass., assignor to
 United Shoe Machinery Corporation, Borough
 of Flemington, N. J., a corporation of New
 Jersey

Application November 4, 1940, Serial No. 364,222

13 Claims. (Cl. 112—50)

The present invention relates to shoe machines, and is herein shown as embodied in an automatic machine for sewing welt shoes, which is substantially similar in construction and mode of operation with that illustrated in a copending application of the present applicant for Shoe machines, Serial No. 364,223, filed November 4, 1940.

The illustrated machine is of the general type in which the shoe is supported upon a jack, and in which the jack and the operating means are moved relatively to transfer the point of operation about the shoe, and to change the relative positions of the shoe and the operating means to cause the shoe to be presented properly to the operating means as the point of operation is transferred around the shoe, all of the relative movements of the shoe and the operating means being produced and controlled by automatically acting mechanism.

While the several mechanisms of the present invention are particularly applicable to the shoe machine above referred to, it is to be understood that the invention in its broad aspects is not limited to use in a fully automatic machine, and also that, except as defined in the claims, the several features of the invention are not limited to any particular construction and arrangement of parts.

The stitch forming and work positioning devices of the illustrated machine include a curved hooked needle which strikes into the work at an angle, passing through portions of the welt, upper and insole for sewing together these parts, and a channel guide which engages in a stitch receiving channel provided in the exposed surface of the insole for positioning the work with relation to the sewing mechanism and about which the shoe is tipped and turned during the progress of the sewing operation to present the shoe properly to the sewing mechanism.

With this conventional construction of the sewing and work positioning devices, difficulty has been encountered in properly locating those stitches of the seam adjacent the breast line of the heel. The shoe, in the condition in which it is presented to the welt sewing mechanism, ordinarily comprises an insole and an upper, together with a counter and a lining, assembled upon and temporarily secured to a last. Owing to the configuration of the last and the assembled parts of the shoe, there tends to be formed an extra thickness or bunch of material at the breast line of the heel which causes the welt when laid in position on the upper to be displaced with respect to the point of support of the shoe provided

by the engagement of the channel guide with the stitch receiving channel of the insole.

In the performance of the welt sewing operation on machines of commercial types in which the shoe is presented to the sewing mechanism by the operator, it is the usual practice for the operator to turn the welt outwardly at the breast line of the heel, and to sharply turn or twist the shoe so that the needle, operating in fixed relation to the channel guide, will not strike too deeply into the work at the breast line of the heel with consequent damage to the appearance of the finished shoe and possible injury to the upper. This manipulation of the shoe when performed manually, requires a high degree of skill on the part of the operator, and as applied to machines in which the shoe is presented to the stitching mechanism by automatic means, becomes even more difficult because of the extreme movements required, and also because of variations from shoe to shoe in the amount by which the upper and welt are displaced.

It is a principal object of the present invention to improve the construction and mode of operation of an inseam sewing machine of the general type having stitch forming devices including a curved needle and work positioning devices cooperating therewith, to cause the position of the shoe with relation to the stitch forming devices to be adjusted during the transfer of the operation about the shoe to compensate for irregularities in the formation of the shoe tending to displace the welt and upper with respect to the guiding contour normally depended upon to locate the shoe with respect to the needle.

It is a further object of the invention to provide in an inseam sewing machine of this description, means for relatively positioning the needle and shoe positioning devices to cause the needle to strike less deeply into the work during those portions of the operation adjacent the breast line of the heel in order to properly place the stitches of the seam with relation to the welt and upper.

Specifically, it is an object of the invention to improve the construction and mode of operation of an automatic shoe sewing machine adapted for sewing welt shoes to cause the stitch forming and work guiding devices to properly position the line of stitching with respect to the welt and upper, particularly during the formation of the initial and final stitches of the seam at the breast line of the heel.

With these and other objects in view, as hereinafter appear, a principal feature of the invention consists in the provision in an inseam

sewing machine having a curved needle and a work positioning member arranged to engage with the sole portion of the shoe, of means for effecting a relative adjustment of the work positioning member and the stitch forming devices including the needle, during continued operation of the stitching mechanism to vary the depth at which the needle strikes into the work.

More specifically, a feature of the invention consists in the provision of automatic means operable during the progress of the sewing operation around the shoe to position the channel guide with relation to the needle to effect predetermined variations of the depth at which the needle strikes into the work.

The several features of the invention consists also of devices, combinations and arrangement of parts hereinafter described and claimed which, together with the advantages to be obtained thereby, will be readily understood by one skilled in the art from the following description taken in connection with the accompanying drawings, in which Fig. 1 is a view in right side elevation of an automatic inseam sewing machine illustrating a preferred form of the present invention; Fig. 2 is an enlarged detail view in right side elevation of applicant's channel guide and associated mechanism for effecting vertical adjustment of the channel guide with respect to the stitch forming mechanism including the needle, the parts being shown in a position of normal adjustment; Fig. 3 is an enlarged detail sectional view in right side elevation, showing substantially the parts in Fig. 2, but taken on a line 3—3 of Fig. 4, and with the channel guide shown in a fully depressed position so that the needle will strike into the work at an abnormally high level; Fig. 4 is a plan view of substantially the parts shown in Figs. 2 and 3; Fig. 5 is a view in front elevation, partly in section, showing the channel guide and its supporting slide assembly in the sewing head of the machine; and Fig. 6 is a detail plan view showing particularly the pattern cam and cam lever for automatically controlling the adjustment of the channel guide.

The automatic inseam sewing machine herein disclosed as embodying the several features of the invention comprises a machine casing built up of a base section 10, a middle or column section 12 and an operating head 14, on which is supported a driving motor 16 for the machine.

The sewing mechanism of the machine mounted in the operating head 14 comprises stitch forming devices adapted for sewing together the insole, upper and the welt of a welted shoe while supported on a last, including a curved hooked needle designed at 18, and work positioning devices including a channel guide 20 which is arranged to engage with a stitch receiving channel formed in the exposed surface of the insole for positioning the shoe with relation to the stitch forming devices. The several cooperating instrumentalities of the stitch forming mechanism are not specifically illustrated, inasmuch as any conventional form of such mechanism may be employed as, for example, that specifically illustrated in applicant's copending application above referred to.

The present machine is provided with a shoe supporting jack and supporting and actuating mechanism for the jack arranged to present the shoe to the sewing mechanism and to automatically transfer the point of operation about the shoe. The lasted shoe, indicated generally at 22, is supported on a jack 24, which may be

of ordinary construction and is not therefore specifically illustrated. The jack is mounted on the upper end of a vertically arranged spindle 26, which is rotatably and swingably mounted on gimbal bearings in the outer end of a horizontally arranged jack supporting arm 28 forming part of a jack supporting assembly adapted for imparting turning, and lateral and longitudinal tipping movements to the shoe about the point of contact of the shoe with the channel guide 20.

During the operation on a shoe, the jack is supported yieldingly upwardly and outwardly to maintain the point of contact of the channel guide with the shoe through connections which include a vertically arranged jack supporting rod 30, pivotally connected at its upper end to the under side of the horizontally disposed arm 28, and at its lower end to a horizontally arranged control lever 32 which is acted upon by springs 34 to force the jack yieldingly upwardly against the work. A tension spring 35, connected between the downward extension of the spindle 26 and the supporting rod 30, tends to swing the jack outwardly to maintain the channel portion of the shoe in engagement with the channel guide. For moving the jack into and out of operating position, there is provided a toggle connection comprising pivotally connected arms 36, 38, the arm 36 being pivoted at 40 on the machine frame, and the arm 38 being pivotally connected with the control lever 32. Mechanism is provided, but not here shown, which is rendered operative upon the jacking of a shoe, to break the toggle connection 36, 38, so that the jacked shoe is moved yieldingly upwardly into operative relationship with the sewing mechanism, and in stopping the machine, to straighten the toggle mechanism and thereby move the shoe outwardly and away from the sewing mechanism.

In accordance with the usual practice in these machines, the operation of the jack is automatically controlled by means of cams on a vertically arranged pattern cam shaft 44, which is power driven through a driving and stopping mechanism from the motor 16. The driving and stopping mechanism of the machine is shown generally in dotted lines in Fig. 1 to include a vertically arranged drive shaft 46, continuously driven from the motor 16, and a main driving clutch comprising a driving element 48 operatively connected with the drive shaft 46, and a driven element 50 which is connected through appropriate connections to drive the sewing mechanism and also to drive the pattern cam shaft 44. Inasmuch as these parts are fully illustrated in applicant's copending application above referred to, and form specifically no part of the present invention, further illustration thereof has been omitted.

In accordance with the present invention, applicant provides means for automatically adjusting the position of the channel guide 20 with relation to the stitch forming devices including the curved hooked needle 18, to vary the depth at which the needle enters the work during the progress of the sewing operation about certain parts of the sole margin of the shoe. The machine disclosed is particularly arranged for the sewing of a welted shoe in which the sewing operation is initiated at the breast line of the heel and extends around the shank and forepart portions of the shoe, terminating again at the breast line of the heel.

Specifically, in accordance with the invention,

applicant proposes to locate the channel guide in a depressed position for the starting position of the machine, and then, during the formation of the initial stitches of the seam, to gradually move the channel guide upwardly to its normal position, which is maintained during the transfer of the point of operation about the shoe, the channel guide again being moved downwardly during the forming of the final stitches of the seam at the termination of the sewing operation at the breast line of the heel. In this manner, applicant has been able to effect adequate compensation for the dislocation of the welt and upper caused by the bunching of material at the breast line of the heel, and to insure the proper location of the initial and final stitches of the seam in the work for properly securing the leading and terminating portions of the welt to the insole and associated upper at the breast line of the heel.

To this end, the channel guide 20 is formed on the lower end of a vertically arranged slide 52, mounted in a guideway 54 in the operating head 14. The slide 52 has formed therein a transverse slot 56, through which extends a cross pin 58, which is journalled in the bearings formed in the operating head. An eccentric cam 60, secured to the cross pin 58 is loosely fitted in the slot 56 to permit a limited vertical movement of the slide 52 and channel guide 20 with relation thereto. A compression spring 62, seated in a vertical recess 64 in the slide 52 and fitted at its lower end with a plunger 66 for engagement with the cross pin 58, tends normally to maintain the slide 52 and channel guide 20 in the normal raised position, which is determined by the position of angular adjustment of the cross pin 58 and eccentric cam 60. The cross pin 58 is provided at one end with a slot 68 adapted to receive a screw driver or similar tool, for the convenient adjustment of the normal operating position of the channel guide 20 with relation to the stitch forming devices including the needle 18. Adjustment in the angular position of the cross pin 58 and eccentric cam 60 is made in setting up the machine to bring the bottom edge of the channel guide 20 substantially in line with the radius of movement of the outside edge of the needle 18. The arrangement of the eccentric cam 60 and the slot 56 is such that the slide 52 is permitted a downward movement against the pressure of its spring 62 of a definite amount which in the illustrated embodiment of the invention is about $\frac{1}{16}$ ".

Further in accordance with the invention, mechanism is provided, which is controlled from the pattern cam shaft 44 of the machine, for automatically controlling the adjustment of the channel guide 29 with relation to the stitch forming devices to vary the depth at which the needle strikes into the work during the progress of the sewing operation about the sole margin of the shoe. This mechanism comprises a cam 70 on the pattern cam shaft 44, and a cam lever 72, supported on the vertical pivot shaft 74 and provided with a roll 76 for engagement with the cam 70. The cam lever 72 is connected by means of a link 78 with one arm of a bell-crank lever 80, the other arm of which is connected by a link 82 with a guide control lever 84 pivotally supported at 86 on the machine head. A forwardly extending arm of the channel guide control lever 84 is arranged for engagement in a notch 88 formed in the slide 52. The contour of the pattern cam 70 is such that at the start-

ing position of the machine the channel guide 20 will occupy its extreme downward position determined by the engagement of the cam 60 with the upper side of the slot 56, so that the needle 18 will strike into the work at an abnormally high level. During the formation of the initial stitches of the seam, the channel guide is gradually raised to its normal operating position determined by the engagement of the under side of the slot 56 with the under side of the eccentric cam 60. During the formation of the final stitches of the seam, the channel guide is again gradually depressed to its extreme low position, so that the needle again is caused to strike into the work at an abnormally high level during the formation of these stitches.

The invention having been described, what is claimed is:

1. An inseam sewing machine arranged for sewing together an insole and associated upper having, in combination, stitch forming devices, including a curved needle, work positioning devices including a work engaging member disposed to determine the depth at which the needle strikes into the work, means for shifting the relative position of the work engaging member and stitch forming devices to vary the depth at which the needle strikes into the work, and means for controlling said shifting means to vary the depth of the stitching in the work during the progress of the sewing operation about the shoe.

2. An inseam sewing machine arranged for sewing together an insole and associated upper having, in combination, stitch forming devices including a curved needle, work positioning devices including a work engaging member shiftable with relation to the stitch forming devices to vary the position of the insole and upper with relation to the needle and thereby to determine the depth at which the needle strikes into the work, and means for controlling the position of the work engaging member to vary the depth of the stitching in the work during the progress of the sewing operation about the shoe.

3. An inseam sewing machine having, in combination, stitch forming devices including a curved needle, work positioning devices including a channel guide, and means operative during the progress of the sewing operation about the shoe for shifting the position of the channel guide with relation to the stitch forming devices to vary the depth at which the needle strikes into the work.

4. An inseam sewing machine having, in combination, stitch forming devices including a curved needle, work positioning devices including a channel guide, and means operative during the progress of the sewing operation about the shoe for shifting the relative positions of the channel guide and stitch forming devices to vary the depth at which the needle strikes into the work.

5. An inseam sewing machine having, in combination, stitch forming devices including a curved needle, work positioning devices including a channel guide, and automatic means operative during the progress of the stitching about the shoe to shift the relative positions of the channel guide and stitch forming devices to vary the depth at which the needle strikes into the work.

6. An inseam sewing machine arranged for sewing together an insole, the associated upper, and a welt having, in combination, stitch forming devices including a curved needle, work positioning devices including a channel guide shiftable to determine the depth at which the needle

strikes into the work, and means for controlling the position of the channel guide to cause the needle to strike into the work at an abnormally high level during the formation of those stitches of the seam adjacent the breast line of the heel.

7. An inseam sewing machine arranged for sewing together an insole, the associated upper and a welt extending from the breast line of the heel around the shank and forward portion of a shoe having, in combination, stitch forming devices including a curved needle, work positioning devices including a channel guide shiftable to determine the depth at which the needle strikes into the work, and automatic means operable during the progress of the stitching about the shoe for shifting the position of the channel guide to cause the needle to strike into the work at an abnormally high level during the formation of the initial stitches leaving the breast line of the heel and at the end of the sewing operation during the formation of the final stitches approaching the breast line of the heel.

8. An inseam sewing machine arranged for sewing together an insole, the associated upper, and a welt having, in combination, stitch forming devices including a curved needle, work positioning devices including a channel guide movable to vary the position of the work with relation to the needle, means for positively stopping the channel guide alternatively in a normal position with respect to the needle, and in a predetermined depressed position for causing the needle to strike into the work at an abnormally high level, and means operable during the progress of the stitching around the shoe to shift the channel guide from one to the other of said positions.

9. An inseam sewing machine arranged for sewing together an insole, the associated upper, and a welt having, in combination, stitch forming devices including a curved needle, work positioning devices including a channel guide, a slide on which the channel guide is mounted for movement to vary the position of the work with relation to the needle, adjustable means for positively stopping the slide and channel guide alternatively in a normal position with respect to the needle and in a depressed position for causing the needle to strike into the work at an abnormally high level comprising a transverse slot in the slide, an eccentric cam supported for angular adjustment on the machine and loosely fitted within said slot, spring means for supporting the slide and channel guide in said normal position, and means for controlling the position of the channel guide during the progress of the stitching about the shoe comprising an element arranged to act on said slide against the pressure of said spring means.

10. In an automatic machine, the combination of an inseam sewing mechanism adapted for sew-

ing together the insole, associated upper and welt, including a curved hooked needle, a channel guide, a shoe supporting jack, means for imparting positioning movement to the jack to present

5 the shoe to the sewing mechanism and to transfer the point of operation about the shoe, means for shifting the relative position of the channel guide and needle to vary the depth at which the needle strikes into the work, and automatic 10 means for controlling said shifting means to vary the depth of the stitching in the work at predetermined points during the progress of the stitching about the shoe.

11. In an automatic machine, the combination 15 of an inseam sewing mechanism adapted for sewing together the insole, associated upper and welt, including a curved hooked needle, a channel guide, a shoe supporting jack, means for imparting positioning movements to the jack to present the shoe to the sewing mechanism and to transfer the point of operation about the shoe, means for shifting the relative position of the channel guide and needle to vary the depth at which the needle strikes into the work, and automatic 20 means for controlling said shifting means to cause the needle to strike into the work at an abnormally high level during the formation of those stitches of the seam adjacent the breast line of the heel.

12. In an automatic machine, an inseam sewing mechanism arranged for sewing together an insole, associated upper and welt, including a curved hooked needle, a channel guide shiftable to vary the depth at which the needle strikes into the work, a shoe supporting jack, supporting and actuating mechanism for the jack arranged to present the shoe to the sewing mechanism and to transfer the point of operation about the shoe, including a pattern cam shaft, and means including a cam on the pattern cam shaft and connections therefrom for controlling the position of the channel guide to vary the depth of the stitching in the work during the progress of the sewing operation about the shoe.

13. In an automatic machine, an inseam sewing mechanism arranged for sewing together an insole, associated upper and welt, including a curved hooked needle, a channel guide, a support on which the channel guide is vertically shiftable 45 with respect to the sewing mechanism including the needle, a shoe supporting jack, supporting and actuating mechanism for the jack arranged to present the shoe to the sewing mechanism and to transfer the point of operation about the shoe, including a pattern cam shaft, and means actuated from the pattern cam shaft for controlling the vertical position of the channel guide.

ALFRED R. MORRILL.
